CLAIM

The ornamental design for a feeder for animals, as shown and described.

DESCRIPTION

FIG. 1 is a perspective view of the feeder for animals of the present design showing the front, top, and second side portions of the feeder for animals in accordance with a first embodiment.

FIG. 2 is a front view of the feeder for animals of the present design showing a front portion of the feeder for animals in accordance with the first embodiment.

FIG. 3 is a back view of the feeder for animals of the present design showing a back portion of the feeder for animals in accordance with the first embodiment.

FIG. 4 is a first side view of the feeder for animals of the present design showing a first side portion of the feeder for animals in accordance with the first embodiment.

FIG. 5 is a second side view of the feeder for animals of the present design showing a second side portion of the feeder for animals in accordance with the first embodiment.

FIG. 6 is a top view of the feeder for animals of the present design showing a top portion of the feeder for animals in accordance with the first embodiment.

FIG. 7 is a bottom view of the feeder for animals of the present design showing a bottom portion of the feeder for animals in accordance with the first embodiment.

FIG. 8 is a perspective view of the feeder for animals of the present design showing the back, bottom, and second side portions of the feeder for animals in accordance with the first embodiment.

FIG. 9 is a perspective view of the feeder for animals of the present design showing the back, top, and first side portions of the feeder for animals in accordance with the first embodiment.

FIG. 10 is a perspective view of the feeder for animals of the present design in an open configuration showing the front, top, and second side portions of the feeder for animals in accordance with the first embodiment.

FIG. 11 is a perspective view of the feeder for animals of the present design in an open configuration showing the back, top, and first side portions of the feeder for animals in accordance with the first embodiment.

FIG. 12 is a perspective view of the feeder for animals of the present design showing the front, top, and second side portions of the feeder for animals in accordance with a second embodiment.

FIG. 13 is a front view of the feeder for animals of the present design showing a front portion of the feeder for animals in accordance with the second embodiment.

FIG. 14 is a back view of the feeder for animals of the present design showing a back portion of the feeder for animals in accordance with the second embodiment.

FIG. 15 is a first side view of the feeder for animals of the present design showing a first side portion of the feeder for animals in accordance with the second embodiment.

FIG. 16 is a second side view of the feeder for animals of the present design showing a second side portion of the feeder for animals in accordance with the second embodiment.

FIG. 17 is a top view of the feeder for animals of the present design showing a top portion of the feeder for animals in accordance with the second embodiment.

FIG. 18 is a bottom view of the feeder for animals of the present design showing a bottom portion of the feeder for animals in accordance with the second embodiment.

FIG. 19 is a perspective view of the feeder for animals of the present design showing the back, bottom, and second side portions of the feeder for animals in accordance with the second embodiment.

FIG. 20 is a perspective view of the feeder for animals of the present design showing the back, top, and first side portions of the feeder for animals in accordance with the second embodiment.

FIG. 21 is a perspective view of the feeder for animals of the present design in an open configuration showing the front, top, and second side portions of the feeder for animals in accordance with the second embodiment; and,

FIG. 22 is a perspective view of the feeder for animals of the present design in an open configuration showing the back, top, and first side portions of the feeder for animals in accordance with the second embodiment.

The broken lines throughout the drawings depict exemplary elements of the feeder that are shown for illustrative purposes only and that form no part of the claimed design.
